(57) **CLAIM**

The ornamental design for a ball mount with integral clevis anchor, as shown and described.

DESCRIPTION

FIG. 1 is a top perspective view of the ball mount with integral clevis anchor design;

FIG. 2 is a bottom perspective view of the ball mount with integral clevis anchor design of FIG. 1;

FIG. 3 is a left side view of the design corresponding to FIGS. 1 and 2;

FIG. 4 is a top view of the design corresponding to FIGS. 1 and 2;

FIG. 5 is a right side view of the design corresponding to FIGS. 1 and 2;

FIG. 6 is a bottom view of the design corresponding to FIGS. 1 and 2;

FIG. 7 is a back view of the design corresponding to FIGS. 1 and 2; and,

FIG. 8 is a front view of the design corresponding to FIGS. 1 and 2.

Wherein a pin latching mechanism is shown in dashed lines for purposes of illustration, but which does not form a part of the design.

1 Claim, 7 Drawing Sheets
